FREDERICK K. FILDES, OF ALTOONA, PENNSYLVANIA

VENTILATING AND MUFFLING APPARATUS FOR ENGINE ROOMS

Application filed November 21, 1930. Serial No. 497,126.

This invention relates to ventilating and muffling apparatus for engine rooms and is particularly adapted to ventilate and muffle the sound within a compartment such as the 5 cab of a locomotive equipped with an internal combustion engine.

The object of the invention is to provide apparatus of comparatively simple and inexpensive construction for effectively deadening 10 the pulsations from the exhaust system of an engine and at the same time to utilize such a muffler as a means for inducing a draft of air through the engine room to ventilate the same and to cool the exhaust piping.

15 When a high powered internal combustion engine is placed in a comparatively small compartment, such as the cab of a locomotive, it is especially desirable to provide means for ventilating the compartment and for eliminating or reducing the noise of the exhaust. Furthermore, the high temperature of the 20 exhaust gases in such an engine necessitates cooling of the exhaust pipes to prevent them from burning out. These desiderata are accomplished according to my invention by 25 providing partitions in the engine room so arranged as to form a conduit substantially surrounding the exhaust system, while permitting access to all other parts of the engine, 30 and placing in this conduit muffling apparatus designed to induce a draft of air from the engine room space to the outside atmosphere, said draft of air surrounding the exhaust piping and continually cooling the same 35 while the engine is running.

Other objects and advantages characterizing my invention will be more fully apparent from the detailed description of one embodiment or example thereof, which follows hereinafter, having reference to the accompanying 40 drawings, whereof:

Fig. I represents a portion of a locomotive cab and a side elevation of an engine therein equipped with ventilating apparatus of my invention; and,

Fig. II represents a cross-section of the same, taken as indicated by the lines II-II of Fig. I.

50 The engine 1 is represented as a conventional type of eight cylinder engine, and is in

the present instance located in the center of a compartment forming the engine room of a locomotive. The side walls of this compartment are shown at 2 and the roof at 3. A longitudinal partition or baffle 4 is secured 55 at its bottom edge to an angle bar 5 at the top of the engine, and at its top edge to the roof 3 of the compartment. An additional longitudinal partition 6 is suspended from the roof 3 and extends downward to a point adjacent the cylinder block 7 of the engine and is supported thereon by brackets 8. A transverse partition 9 is also preferably provided, at the end of the engine, the latter partition being likewise shown suspended from the 60 roof of the cab and extending downward to a point adjacent the cylinder block 7 of the engine. The above mentioned partitions form a conduit open at one end to the engine room at the engine and at the other end to the atmosphere outside the engine room through the opening 11 in the roof of the cab.

Secured to the cylinder block 7 at one side of the engine are a number of elbows 12, corresponding to the number of cylinders, 75 which serve as the outlets for the exhaust gases from the engine. Associated with each elbow 12 there is an expansion joint 13 and fitted to each expansion joint there is an exhaust pipe 14. All of the exhaust pipes 14 80 terminate at their upper ends in an exhaust chamber 15 which is in the form of a box of relatively large cross-sectional area and of a length substantially corresponding to that of the engine.

85 The chamber 15 is conveniently mounted on the roof 3 of the engine compartment by means of suspension members in the form of angle irons 16 and straps 17 and 18. At the bottom, the chamber 15 is provided with 90 pipe connections 19 which engage the ends of exhaust pipes 14. Extending diagonally across the interior of the chamber are a series of spaced baffles 20 which obstruct direct flow 95 of the exhaust gases from the pipes 14 to the chamber outlets 21. Each baffle 20 is in the form of a rectangular plate disposed across the interior of the chamber 15 directly between a pipe 14 and an outlet 21. It will be noted, however, that while there are eight 100

exhaust pipes shown in the drawings, the chamber 15 is provided with only seven outlets and baffles. The large volume of the chamber 15 and the position of the baffles 5 20, as well as the difference in number between the inlets and outlets, cause the exhaust gases from one cylinder to mix with those from another cylinder in the chamber 15 rather than to pass directly out of the chamber, and accordingly the chamber tends to 10 smooth out the pulsations of the engine exhaust and acts as a muffler.

The exhaust chamber outlets 21 are in the form of nozzles of annular section and are directed vertically upward toward the opening 15 11 in the roof of the cab. Spaced at a predetermined distance from the top of each exhaust nozzle 21 and in vertical line therewith there is a stack 22 having its lower end flared 20 at 23 to form a venturi. The stacks 22 are supported by a hood 24 which covers the opening 11 in the roof of the compartment. Each stack is concentric with an exhaust nozzle 21 and the row of stacks is preferably 25 disposed along the center line of the cab. I have found that by varying the distance between the bottom of a Venturi pipe and the top of an exhaust nozzle, the sound of the pulsations from the engine exhaust may be varied and that there is a definite relation 30 between the spacing of the nozzles from the venturis and the audibility of the noise from the engine. Accordingly, this distance is determined in advance as best suits the particular engine to which the apparatus of this 35 invention is applied.

As the exhaust gases pass from the nozzles 21 into the stacks 22 and thence to the atmosphere, they tend to create a vacuum in the 40 space surrounding the nozzles 21, beneath the flared ends of the stacks and accordingly a venturi action is set up inducing a strong draft of air from the conduit between the partitions 4 and 6 into the stacks 22. Furthermore, the heat of the exhaust naturally causes 45 air to flow by convection through this conduit to the atmosphere. The path of the air as shown by the arrows is from the engine where the air is warmest, directly into the 50 space between partitions 4 and 6 where it divides, part of the air passing upward on one side of the exhaust piping and part on the other side. Eventually the air reaches a point adjacent the nozzles 21 from whence 55 it is ejected through stacks 22 to the atmosphere. In its passage the air serves to cool the exhaust pipes 14 and reduce their temperature to such an extent that the danger of 60 their burning out or unduly expanding when the engine is running at top speed is eliminated.

It will be noted that the conduit for the passage of air from the engine room is formed in such manner that it does not materially reduce 65 the available engine room space nor

prevent access to the engine. Furthermore, the exhaust piping being mounted independently of the stacks, need not be rigidly restricted against movement incident to expansion and contraction of the parts, but 70 may, as shown, possess appreciable flexibility.

While I have shown one form which the invention may take and have described a particular arrangement of parts, it will be apparent that various changes may be made in the form of the apparatus without departing from the spirit of my invention as defined in the claims hereto annexed.

Having thus described my invention, I 80 claim:

1. Engine room ventilating apparatus comprising a stack in the form of a Venturi pipe at the top of the engine room, partitions in the engine room substantially surrounding the exhaust piping of the engine and forming a conduit having one end open to the engine room and the other end terminating in said stack, and a muffler in said conduit having an exhaust nozzle at the base of said stack, 90 whereby a draft is induced in said conduit by venturi action.

2. Engine room ventilating apparatus comprising a stack in the form of a Venturi pipe at the top of the engine room, partitions in the engine room substantially surrounding the exhaust piping of the engine and forming a conduit having one end open to the engine room at said engine and having the other end terminating at said stack, and sound muffling means in said conduit, said means including an exhaust nozzle at the base of said stack and axially aligned therewith whereby air from the engine room is caused to pass through said conduit cooling the exhaust piping of the engine.

3. Engine room ventilating apparatus comprising partitions in the engine room forming a conduit with one end open to the engine room and the other end open to the atmosphere outside the engine room, a plurality of exhaust pipes leading from the engine and terminating in a chamber, said exhaust pipes and chamber being disposed within said conduit, exhaust nozzles on said chamber, and stacks in the form of Venturi pipes having flared ends vertically spaced from said exhaust nozzles to provide a gap at which air passing from said conduit may commingle with the exhaust gases and be ejected from the engine room.

4. Engine room ventilating apparatus comprising stacks in the form of Venturi pipes at the top of the engine room, a conduit substantially surrounding the exhaust piping of the engine where said piping leaves the engine while permitting access to the major portion of the engine, said conduit having one end open to the engine room at said engine and the other end terminating at said 130

stacks, and combined sound muffling and draft inducing means in said conduit, said means including exhaust nozzles disposed beneath said stacks and axially aligned therewith.

5. Engine room ventilating apparatus comprising partitions in the engine room forming a conduit with one end open to the engine room at the engine and the other end open to the atmosphere outside the engine room, a plurality of exhaust pipes leading from the engine and terminating in a muffler, said pipes and muffler being disposed within said conduit, a plurality of stacks at the top 10 of said room extending therealong for substantially the length of the engine and forming the outside end of said conduit and means whereby the exhaust gases from said muffler as they pass to said stacks are caused to induce a draft of air through said conduit.

15. Engine room ventilating apparatus comprising stacks in the form of Venturi pipes at the top of the engine room, a partition from the top of the engine to the top of the engine room, an additional partition forming with said first partition a conduit substantially surrounding the exhaust piping of the engine while permitting access to the engine with one end open to the engine 20 room and the other end terminating at said stacks, and combined sound muffling and draft inducing means in said conduit, said means including exhaust nozzles disposed beneath said stacks and axially aligned therewith.

25. Engine room ventilating apparatus comprising an engine, exhaust piping leading therefrom to a chamber, nozzles on said chamber, baffles in said chamber preventing a 30 direct flow of exhaust gases to said nozzles, and stacks disposed above said nozzles and mounted independently of said chamber, said stacks being in the form of Venturi pipes having their lower ends vertically spaced 35 from said nozzles and in communication with the air in the engine room, whereby a draft of air is induced through the engine room incident to the passage of the exhaust gases from said nozzles to said stacks.

40. In testimony whereof, I have hereunto signed my name at Altoona, Pennsylvania, this 19th day of November, 1930.

FREDERICK K. FILDES.
